UNITED STATES PATENT OFFICE.

FREDRICK W. COFFING, OF DANVILLE, ILLINOIS, ASSIGNOR TO OTTO WALTER, OF PERRYSVILLE, INDIANA.

HIGH-SPEED FREE-CHAIN HOIST.

Application filed July 22, 1924. Serial No. 727,527.

This invention relates to a high speed free chain hoist, and the object of this invention is to provide a light weight and high speed hoist which may be readily and conveniently carried from place to place so as to be well adapted for use by linemen and others who require the use of such an instrument in elevating and tensioning heavy rods, wires, cables or the like.

10 Another important object is to provide a hoist of this character and having these advantages and wherein the chain is automatically and completely housed to prevent it from becoming entangled with surrounding objects or otherwise.

A still further object is to provide a hoist of this character wherein a high degree of power is applied to the chain and wherein the chain may be held in any position or adjustment and conveniently controlled irrespective of whether it is being payed out of or drawn into the housing.

A still further object is to provide a chain hoist having these advantages and which is of simple and durable construction, reliable in operation, easy and convenient to control and comparatively inexpensive to manufacture.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a view in side elevation with parts broken away and shown in section and illustrating one embodiment of the invention;

Figure 2 is a view in section on line 2—2 of Figure 1, the chain being omitted and parts being shown in elevation for the sake of illustration;

Figure 3 is a fragmentary view in section on line 3—3 of Figure 2;

Figure 4 is a view of the hand crank and associated parts in side elevation, a portion of the hand crank being broken away and parts being shown in section for the sake of illustration;

Figure 5 is a view in elevation, showing the inner side of the handle;

Figure 6 is a detail view, showing the release mechanism for the locking pawl;

Figure 7 is a view, partly in section and partly in elevation, showing the swivel connection of the hook to the chain;

Figure 8 is a view in horizontal section on line 8—8 of Figure 1; and

Figure 9 is a similar view on line 9—9 of Figure 1.

Referring to the drawings, the numeral 10 designates generally the housing or casing which is made up of a pair of similar parts 65 including circular side walls 11 having lateral offset peripheral flanges 12 secured to each other by screws or other suitable fastening means 13. The flanges 12 space the side walls 11 in parallel relation and to such an extent as to define a magazine 14 for the chain which is designated at 15. The lateral extent of the magazine is such as to permit the links of the chain to freely move relative to the walls 11 of the housing but these links are constrained to movement in the plane of the housing. This permits the chain to be readily moved into the housing or to be readily withdrawn therefrom without danger of its links becoming entangled 75 with each other or with surrounding objects.

A gear casing 16 is integrally formed with the parts of the housing and in the side walls of the gear casing a shaft 17 is rotatably mounted. A sprocket wheel 18 is keyed or otherwise fixed to the shaft 17 and its teeth which engage the links of the chain 15 operate in proximity to a wall 19 of the gear casing 16, the wall 19 providing a guide or track for the chain 15 while the same is being moved into the magazine 14 or being paid out of the same by the sprocket wheel 18.

A hand crank 20, which constitutes an operating element, is provided for imparting motion to the shaft 17 and this hand crank has a hub 21 rotatably fitted on one end of the shaft 17, and held against axial displacement by means of a screw 22 and washer 23 and by means of the engagement of the flange 24 of the hub with elements to be later described. A ratchet wheel 25 is fixed to the shaft 17 and in the assembly is located within the flange 24 of the hub of the hand lever 20. This ratchet wheel has teeth provided with inclined and vertical faces. A 100 pawl 26 is pivotally mounted, as at 27, on the handle 20 and is controlled by an angular and pivoted finger piece 28 pivotally mounted on the handle and connected by a rod 29 with a lug 30 integral with the hub 110

of the pawl 26. The pawl 26 and ratchet wheel 25 provides a pawl and ratchet connection or more generally a one-way driving connection between the hand crank or operating element and the shaft. The hand lever 20 is of channel form so as to house the rod 29 and similar parts. A spring 31 is provided and coacts with the flange of the handle 20 and with the pawl 26 to urge the pawl into engagement with the teeth of the ratchet wheel 25. With this arrangement when the hand crank or hand lever 20 is rotated in one direction it will impart rotary movement to the ratchet wheel 25 and consequently to the shaft 17 and sprocket wheel 18 unless the finger piece 28 is pressed inwardly to disengage the pawl 26 from the teeth of the ratchet 25. Of course the parts are arranged so that when the hand crank 20 is turned in the direction in which the pawl 26 may be effective to rotate the ratchet 25, the shaft 17 and the sprocket wheel 18 will be rotated in a clockwise direction, as viewed in Figure 1 so as to pull the chain 15 into the magazine 14 of the housing.

In order to control the reverse rotation of the sprocket wheel 18 that is the rotation in a counterclockwise direction as viewed in Figure 1, a locking pawl 35 is provided and is pivotally mounted, as at 36, within the gear casing 16. The outer end of this pawl is engageable with the teeth of the sprocket 18 to hold the sprocket against reverse rotation and a spring 37 is provided for urging the outer end of the pawl 35 into engagement with the teeth of the sprocket 18 for this purpose.

Releasing mechanism is provided for the locking pawl 35 and this releasing mechanism is preferably controlled from the hand crank 20 as will presently be described. It will be noted that the pawl 35 is provided with a camming surface 38 with which the teeth of the sprocket 18 coact to throw the pawl 35 out of engagement with the teeth when the sprocket 18 is being rotated to draw the chain 15 into the housing. One side of the outer end of the locking pawl 35 is formed with an outwardly extending and laterally offset lip 39 which is disposed out of the plane of the teeth of the sprocket 18 and which coacts with a lug 40 integrally formed with or otherwise rigidly secured to an oscillatable control plate 41. This control plate 41 is disposed to one side of the gear casing 16 and is mounted for limited rotation on the shaft 17. The lug 40 projects laterally from the plate 41 and operates in an arcuate opening 42 formed in the gear casing. In one position in the opening 42 the lug 40 engages the lip 39 and holds the pawl 35 out of engagement with the teeth of the sprocket 18 as shown in Fig. 3. In its other position in the opening 42 the lug 40 is out of the field of movement of pawl 35

and does not interfere with the engagement of this pawl with the teeth of the sprocket 18. A coil spring 44 encircles the shaft 17 between the gear casing 16 and the plate 41 and one end of the spring 44 is secured to the gear casing while the other end is secured to the plate 41 by being wrapped around or otherwise connected to the lug 42. This spring 44 is of the torsional type and is tensioned so that it tends to move the control plate 41 and the lug 40 to such position in the opening 42 that the lug 40 will engage the lip 39 of the pawl 35 and hold the pawl 35 out of engagement with the teeth of the sprocket 18. Thus whenever a tooth of the sprocket 18 coacts with the camming surface 38 of the pawl 35 to throw the pawl 35 away from the teeth 18, the spring 44 effects a quick rotation of the plate 41 to bring the lug 40 into engagement with the lip 39 of the pawl to hold the pawl out of engagement with the teeth of the sprocket.

The periphery of the control plate 41 is formed with teeth 45 having inclined and vertical faces, and with these teeth 45 a pawl 46, pivotally connected, as at 47, to the hand crank 20, coacts. A spring 48 urges the pawl 46 into engagement with the teeth 45 of the control plate 41. This pawl 46 may be disengaged from the teeth 45 by gripping the handle member 20^a of the hand crank since an operating member 50 for the pawl 46 has an offset end 51 pivotally connected, as at 52, to the end of the handle member 20^a, and since this operating member 50 is permitted to swing for a limited distance in a slot 53 formed in the handle member 20^a. One end of the operating member is connected by a rod 54 to the pawl 46.

With this arrangement should the hand crank 20 be released during the time the chain is being drawn into the magazine 14 of the housing 10, the chain will not freely pay out even though a heavy load be applied thereto for as soon as the chain starts to pull out of the housing the shaft 17 will be rotated and the hand crank 20 will be reversely rotated with the shaft 17. This movement of the hand crank 20 causes the pawl 46 to turn the control plate 41 so as to disengage the lug 40 from the lip 39 of the pawl 35 whereupon the spring 37 at once forces the pawl 35 into engagement with the teeth of the sprocket to lock the same against reverse movement. If it is desired to permit the chain to pay out it is only necessary to grip the handle member 20^a of the crank 20 while the hand crank is reversely rotated for such gripping of the handle member will depress the operating member 50 so as to disengage the pawl 46 from the teeth 45 of the control plate 41 and permit the lug 40 to engage the lip 39 and to hold the locking pawl 35 out of engagement with the teeth of the sprocket 18.

In order to limit the movement of the control plate 41 and also the movement of the hand crank 20 in the reverse direction to the extent necessary to release the pawl 35 a fixed ratchet wheel 55 is secured to the gear casing 16. This ratchet wheel 55 is of annular form and a guide flange 56 integral- 5 ly formed with the plate 41 coacts with the opening of this annular ratchet wheel 55 to constrain the plate 41 to proper movement. The ratchet wheel 55 has substantially the same circular measurements as the plate 41 although the ratchet wheel 45 is somewhat heavier in its construction. The 10 pawl 46 is of sufficient width to coact with the ratchet wheel 55 as well as with the teeth 45 of the plate 41. The teeth of the ratchet wheel 55 are spaced a sufficient distance from each other about the periphery 15 of the wheel 55 to permit the pawl 46 to actuate the release plate 41 before it engages any teeth on the ratchet wheel 55. In assembly the teeth 45 are staggered with respect to the teeth of the wheel 55 as clearly shown 20 in Figure 4 and the pawl 46 is normally engaged with these teeth 45 and does not engage the teeth of the ratchet wheel 55 until the plate 41 has been moved to such position as to release the pawl 35. 25 A hook 60 is swivelly connected to the housing 10 by means of an enlarged head 61 rotatably fitted in a socket 62 provided on the housing 10. The head presents a shoulder 63 which engages with a wall of 30 the socket 62 to prevent the hook from being pulled from the socket. It will now be understood that there is provided in this manner a pivotal mounting for the housing and it is proposed to provide also means 35 for locking said housing in a predetermined position upon said pivotal mounting. For this latter purpose the head 61 has a plurality of slots 65 formed in its periphery, four slots at angular intervals of 90° preferably being provided. A latch 66 is pivotally mounted on the housing 10, as indicated at 67, the housing being recessed to permit the latch to partake of its operative movements. This latch 66 is selectively engageable with the slots 65 of the head 61 to lock the housing in a predetermined position upon its pivotal mounting. A spring 40 68 is provided for urging the latch into engagement with the slots of the head. Of course the latch may be manually released when it is desirable for the housing to pivot or swivel on its support. 45

A hook 70 is swivelly connected to the chain 15. 50 The chain hoist which constitutes the present invention may be readily carried from place to place and may be suspended from any suitable support by the hook 60. The hook 70 may be readily connected to the object to be elevated or to be pulled. 55

A powerful pull may be imparted to the chain 15 by rotating the hand crank 20 and the chain is automatically held in any position whenever the hand crank 20 is released. In crowded quarters the advantages of a ratchet action is had between the hand crank 20 and the shaft 17. The load or object connected to the hook 61 may be readily lowered or paid out by moving the hand crank 20 in a direction to pull the load upwardly a slight distance and then permit the hand crank to move in a reverse direction while gripping the handle member 20^a thereof so as to swing the operating member 51 about its pivot 52 to provide for the action herein above described. The chain when drawn into the housing coils itself in the magazine thereof and is not liable to become entangled. At the same time the chain readily pays out. Before gripping the handle member 20^a and reversely rotating the same it may be necessary to rotate the same forwardly to a slight extent that is in a direction such as to throw the pawl 35 to disengaged position. 90

I claim:

1. In a chain hoist, a housing having spaced walls defining a magazine, said housing also having a guide leading into the magazine, a chain extending through the guide into the magazine, and means coacting with the chain for drawing the same into the magazine or controlling the paying out therefrom the spaced walls of the magazine coacting with the chain to cause the same to automatically and nonentanglingly arrange itself when drawn into the housing. 95

2. In a chain hoist, a housing made up of a pair of similar parts having curved outlined and substantially flat side walls and offset parallel flanges secured together, the side walls and the peripheral flanges of the housing defining a magazine, the housing also having a guide leading into the magazine, a chain extending through the guide into the magazine and means coacting with the chain for drawing the same into the magazine or controlling the paying out thereof, the side walls and the flanges of the housing coacting with the chain to cause the same to automatically and nonentanglingly arrange itself when drawn into the housing. 110

3. In a chain hoist, a shaft, a sprocket wheel fixed to the shaft, a completely rotatable and reversible hand crank having a pawl and ratchet connection with the shaft for rotating the same in one direction, and means independent of the pawl and controllable from the hand crank for preventing reverse movement of the sprocket wheel. 120

4. In a chain hoist, a shaft, a sprocket wheel fixed to the shaft, a hand crank having a pawl and ratchet connection with the shaft for rotating the same in one direction, means controllable from the hand crank for preventing reverse movement of the sprocket. 130

et wheel and including a locking pawl cooperable with the sprocket wheel for preventing reverse movement thereof, said locking pawl having a camming surface with which the teeth of the sprocket coact to throw the locking pawl away from the sprocket when the sprocket is being rotated forwardly, a spring actuated control plate having a lug engageable with the locking pawl to hold the same disengaged, and means carried by the hand crank and cooperable with the control plate for shifting the same so as to disengage the lug from the locking pawl when the hand crank is reversely rotated.

5. In a chain hoist, a shaft, a sprocket wheel fixed to the shaft, a hand crank having a pawl and ratchet connection with the shaft for rotating the same in one direction, a locking pawl cooperable with the sprocket wheel for preventing reverse movement thereof, said locking pawl having a camming surface with which the teeth of the sprocket coact to throw the locking pawl away from the sprocket when the latter is being rotated forwardly, a spring-actuated control plate having a lug cooperable with the locking pawl to hold the same disengaged, said control plate having peripheral ratchet teeth, a pawl carried by the hand crank and cooperable with the teeth of the control plate, a spring for urging the pawl into engagement with the teeth of the control plate, manually operable means carried by the hand crank for disengaging the pawl from the control plate, and a fixed ratchet connected to the housing for limiting the movement of the control plate and pawl.

6. In a chain hoist, a shaft support, a shaft rotatable therein, a sprocket wheel fixed to the shaft, a hand crank having a pawl and ratchet connection with the shaft for rotating the latter in one direction, means independent of the pawl in all phases of the operation and controllable from the hand crank for preventing reverse movement of the wheel.

7. In a chain hoist, the combination of a magazine having a pair of spaced walls of chain width spacing, and a chain receivable by said magazine in non-entangling re-

lation for self-positioning therein independent of the magazine position.

8. In a chain hoist, the combination of a magazine having a pair of spaced walls of chain width spacing, a chain receivable by said magazine in non-entangling relation for self-positioning therein independent of the magazine position, a pivotal support for said magazine eccentric of the same, and means for locking said magazine to said pivotal support in adjusted position.

9. In a chain hoist, a shaft support, a shaft rotatably supported thereby, a handle, an operating element thereon, a one-way driving connection between said operating element and the shaft, a single means for preventing reverse rotation of the shaft with respect to the support and the handle, and releasing means independent of said one-way driving connection in all phases of the operation for releasing said single means.

10. In a chain hoist, a shaft, an operating element therefor, a pawl and ratchet connection between the operating element and the shaft, means for preventing reverse movement of the shaft, and releasing mechanism independent of the pawl and controllable from the said operating element.

11. In a chain hoist, a shaft, an operating element therefor, a one-way driving connection between the shaft and the operating element for rotating the same in one direction, means for preventing reverse movement of the shaft, said operating element having a handle member, and a grip-controlled releasing mechanism carried by said handle member and engageable with said means for releasing the same.

12. In a chain hoist, a shaft, a sprocket wheel fixed to the shaft, an operating element for the shaft, a one-way driving connection between the operating element and the shaft, a locking pawl cooperable with the sprocket wheel for preventing reverse rotation of the shaft, and releasing mechanism for said locking pawl controlled from said operating element independent of the position thereof.

FREDRICK W. COFFING.
